ders, pastes, soluble powders, dusting agents, granules, etc. These are prepared in known manner, for instance by extending the active compounds with dispersible liquid diluent carriers and/or dispersible solid carriers optionally with the use of carrier vehicle assistants, e.g. surface-active agents, including emulsifying agents and/or dispersing agents, whereby, for example, in the case where water is used as diluent, organic solvents may be added as auxiliary solvents (cf. Agricultural Chemicals, March 1960, pp. 35-38). The following may be chiefly considered for use as carrier vehicles for this purpose: dispersible liquid diluent carriers including inert organic solvents, such as aromatic hydrocarbons (for instance, benzene, toluene, xylene, etc.), halogenated, especially chlorinated, aromatic hydrocarbons (for instance, chlorobenzenes), paraffins (for instance, petroleum fractions), chlorinated aliphatic hydrocarbons (for instance, methylene chloride, etc.), alcohols (for instance, methanol, ethanol, propanol, butanol, etc.), ethers, ether-alcohols (for instance, glycol monomethyl ether, etc.), amines (for instance, ethanolamine, etc.), amides (for instance dimethyl formamide, etc.), sulfoxides (for instance, dimethyl sulfoxide, etc.), ketones (for instance, acetone, etc.), and/or water; as well as dispersible inert finely divided solid carriers, such as ground natural minerals (for instance, kaolins, alumina, silica, chalk, i.e. calcium carbonate, talc, kieselguhr, etc.), and ground synthetic minerals (for instance, highly dispersed silicic acid, silicates, e.g. alkali silicates, etc.); whereas the following may be chiefly considered for use as carrier vehicle assistants, e.g. surface-active agents, for this purpose: emulsifying agents, such as non-ionic and/or anionic emulsifying agents (for instance, polyethylene oxide esters of fatty acids, polyethylene oxide ethers of fatty alcohols, alkyl sulfonates, aryl sulfonates, etc., and especially alkyl arylpolyglycol ethers, magnesium stearate, sodium oleate, etc.); and dispersing agents, such as lignin, sulfite waste liquors, methyl cellulose, etc.

As will be appreciated by the artisan, the active compounds according to the instant invention may be employed alone or in the form of mixtures with one another and/or with such solid and/or liquid dispersible carrier vehicles and/or with other known compatible active agents, especially plant protection agents, such as other herbicides, fungicides, insecticides, bactericides, etc., if desired, or in the form of particular dosage preparations for specific application made therefrom, such as solutions, emulsions, suspensions, powders, pastes, and granules which are thus ready for use.

As concerns commercially marketed preparations, these generally contemplate carrier composition mixtures in which the active compound is present in an amount substantially between about 0.1 and 95% by weight, and preferably 0.5 and 90% by weight, of the mixture, whereas carrier composition mixtures suitable for direct application or field application generally contemplate those in which the active compound is present in an amount substantially between about 0.01 and 2.0%, preferably 0.01 and 0.8%, by weight of the mixture. Thus, the present invention contemplates over-all compositions which comprise mixtures of a dispersible carrier vehicle such as (1) a dispersible carrier solid, and/or (2) a dispersible carrier liquid, such as an inert organic solvent and/or water, preferably including a surface-active effective amount of a carrier vehicle assistant, e.g. a surface-active agent, such as an emulsifying agent and/or a dispersing agent, and an amount of the active compound which is effective for the purpose in question and which is generally between about 0.01 and 95%, by weight of the mixture.

While the active compounds can be used according to the pre-emergence method, i.e. before emergence of the cultivated plants, they are particularly effective also when used according to the post-emergence method.

Generally, the amounts of active compounds used for actual application to the agricultural area may be varied

within fairly wide ranges, such as for example substantially between about 0.1-5 kg. of active compound per hectare, preferably between about 0.5-3 kg./hectare. Of course, where the active compound is used in admixture with a carrier vehicle, the content of active compound in the composition mixture actually applied is, in general, substantially between about 0.1 and 2%, and preferably between about 0.2 and 0.8%, by weight of the mixture as aforesaid, yet the mixture is applied such that the active compounds are used in said amounts between about 0.1-5 kg./hectare.

The inventive compositions also can be used by the so-called ultra-low-volume process with good success. In this process it is possible to use formulations containing up to 95% of active ingredients or even the 100% active substance alone.

Furthermore, the present invention contemplates methods of selectively controlling or combating undesired plants, e.g. weeds and the like, which comprise applying to at least one of (a) such weeds and (b) their habitat, i.e. the locus to be protected, a herbicidally effective amount of the particular active compound of the invention alone or together with a carrier vehicle as noted above. The instant formulations or compositions are applied in the usual manner, for example, by spraying, atomizing, scattering, dusting, watering, sprinkling, and the like, whether for pre-emergence application to the soil or post-emergence application to the weeds.

It will be realized, of course, that in connection with the pre-emergence use of the instant compounds as well as the post-emergence use thereof, the concentration of the particular active compound utilized alone or in admixture with the carrier vehicle will depend upon the intended application and may be varied within a fairly wide range depending upon the weather conditions, the purpose for which the active compound is used, and the plants which are to be controlled or protected. Therefore, in special cases, it is possible to go above or below the aforementioned concentration ranges.

The following examples illustrate, without limitation, the herbicidal activity of the particular active compounds of the present invention.

EXAMPLE 1

Post-emergence test/outdoors/spray powder

Inert carrier material: 0.25 parts by weight kaolin and

silicic acid (3:1)

Protective colloid: 0.03 parts by weight lignin sulfate

Dispersing auxiliary: 0:15 parts by weight hydroxyaryl-sulfonic acid formaldehyde condensate

To produce a suitable preparation of the particular active compound, 1 part by weight of such active compound was mixed with the stated amounts of formulation auxiliaries and the resulting concentrate was then diluted with water to the desired final concentration.

Outdoor plots with test plants which had a height of about 3-10 cm. were sprayed with such an amount of the given active compound preparation that a uniform wetting of the plants occurred. The amount of active compound applied per unit area is decisive. After three weeks the degree of damage to the plants was determined and characterized by the values 0-5, which have the following meaning:

0 no effect

1 a few slightly burnt spots

2 marked damage to leaves

3 some leaves and part of stalks partially dead

4 plant partially destroyed

5 plant completely dead

The particular active compounds tested, the amounts used and the results obtained can be seen from the following Tables 1a and 1b.

EXAMPLE 2

Pre-emergence test/outdoors/spray powder

Inert carrier material: 0.25 parts by weight kaolin and silicic acid (3:1)

Protective colloid: 0.03 parts by weight lignin sulfate

Dispersing auxiliary: 0.15 parts by weight hydroxyarylsulfonic acid formaldehyde condensate

To produce a suitable preparation of the particular active compound, 1 part by weight of such active compound was mixed with the stated amount of formulation auxiliaries and the resulting concentrate was then diluted with water to the desired final concentration.

Shortly after the sowing of the test plants outdoors, the individual plots were watered with such an amount of the given active compound preparation as was necessary for a uniform wetting of the surface of the soil. The con-

centration of the active compound in the preparation is of no importance; only the amount of active compound applied per unit area is decisive.

After 5 weeks, the degree of damage to the test plants was determined and characterized by the values 0-5, which have the following meaning:

- 65 0 no effect
- 66 1 slight damage or delay in growth
- 67 2 marked damage or inhibition of growth
- 68 3 heavy damage and only deficient development or only 50% emerged
- 70 4 plants partially destroyed after germination or only 25% emerged
- 75 5 plants completely dead or not emerged

The particular active compounds tested, the amounts used and the results obtained can be seen from the following Tables 2a and 2b.

EXAMPLE 3

Post-emergence test

Solvent: 5 parts by weight acetone

Emulsifier: 1 part by weight alkylaryl polyglycol ether

To produce a suitable preparation of the particular active compound, 1 part by weight of such active compound is mixed with the stated amount of solvent, the stated amount of emulsifier is added and the resulting concentrate is then diluted with water to the desired final concentration.

Test plants which have a height of about 5-15 cm. are sprayed with the given active compound preparation until

just dew moist. After three weeks, the degree of damage to the plants is determined and characterized by the values 0-5, which have the following meaning:

- 0—no effect
- 1—a few slightly burnt spots
- 2—marked damage to leaves
- 3—some leaves and parts of stalks partially dead
- 4—plant partially destroyed
- 5—plant completely dead

The particular active compounds tested, their concentrations and the results obtained can be seen from the following Table 3.

TABLE 3

EXAMPLE 4

Pre-emergence test

Solvent: 5 parts by weight acetone

Emulsifier: 1 part by weight alkylaryl polyglycol ether

To produce a suitable preparation of the particular active compound, 1 part by weight of such active compound is mixed with the stated amount of solvent, the stated amount of emulsifier is added and the resulting concentrate is then diluted with water to the desired final concentration.

Seeds of the test plants are soon in normal soil and, after 24 hours, watered with the given active compound preparation. It is expedient to keep constant the amount of water per unit area. The concentration of the active compound in the preparation is of no importance, only

35 the amount of active compound applied per unit area being decisive. After three weeks, the degree of damage to the test plants is determined and characterized by the values 0-5, which have the following meaning:

40 0 no effect

1 slight damage or delay in growth

2 marked damage or inhibition of growth

3 heavy damage and only deficient development or only 50% emerged

45 4 plants partially destroyed after germination or only 25% emerged

5 plants completely dead or not emerged.

The particular active compounds tested, the amounts applied and the results obtained can be seen from the following Table 4.

TABLE 4
Pre-emergence test

The process for producing the particular new compounds of the present invention is illustrated, without limitation, by the following further examples.

20

EXAMPLE 5

(III₇)

19 g. 3-chloro-4-trifluoromethyl-phenyl isocyanate are dissolved in 50 ml. chlorobenzene, and 34 ml. of a 50% aqueous dimethyl amine solution are added at 20–30° C., with intensive stirring. The resulting precipitate is filtered off with suction and, after drying, 18 g. N-(3-chloro-4-trifluoromethyl-phenyl)-N',N'-dimethyl-urea of M.P. 150–152° C. are obtained.

The 3-chloro-4-trifluoromethyl-phenyl isocyanate used as starting material can be prepared as follows:

(i) Preparation of 3-chloro-4-methyl-phenyl isocyanate

To a solution of 450 g. phosgene in 1.5 liters benzene there is added dropwise at 0–5° C. a solution of 425 g. 3-chloro-4-methyl aniline in 1.75 liters chlorobenzene. While introducing phosgene, the mixture is heated to 120° C., a clear solution forming after about 1 hour. By distillation there are obtained 356 g. of the above isocyanate, i.e. 3-chloro-4-methyl-phenyl isocyanate, of B.P. 113–114° C./20 mm. Hg.

(ii) Preparation of 3-chloro-4-trichloromethyl-phenyl isocyanate

690 g. 3-chloro-4-methyl-phenyl isocyanate are chlorinated under ultra-violet irradiation for 8 hours at 180–200° C. A weight increase of about 300 g. is obtained. The desired 3-chloro-4-trichloromethyl-phenyl isocyanate boils at B.P. 173–174° C./16 mm. Hg. Yield: 618 g.

(iii) Preparation of 3-chloro-4-trifluoromethyl-phenyl isocyanate

136 g. 3-chloro-4-trichloromethyl-phenyl isocyanate are added dropwise within about 2 hours at 0° C. to 150 ml. hydrogen fluoride. After stirring for several hours until the cessation of evolution of HCl, the hydrogen fluoride is distilled off in a vacuum. The crystalline residue is distilled at 120° C. under nitrogen. Yield: 77 g., B.P. 93° C./14 mm. Hg.

EXAMPLE 6

In the same manner as described for the production of N-(3-chloro-4-trifluoromethyl-phenyl)-N',N'-dimethyl-urea in Example 5 the following compounds are obtained:

(IV₈)

25

EXAMPLE 7

(V₁)

Using corresponding molar amounts of each of the following amines with 3-chloro-4-trifluoromethyl-phenyl isocyanate in accordance with the procedure of Example 5, as the case may be:

- (a) tert.-butyl amine and 3-chloro-4-trifluoromethyl-phenyl isocyanate;
- (b) di-isopropyl amine and 3-chloro-4-trifluoromethyl-phenyl isocyanate; and
- (c) methyl-n-butyl-amine and 3-chloro-4-trifluoromethyl-phenyl isocyanate;

the corresponding final compounds, respectively, are produced:

- (a') N-(3-chloro-4-trifluoromethyl-phenyl)-N'-tert.-butyl-urea;
- (b') N-(3-chloro-4-trifluoromethyl-phenyl)-N',N'-di-isopropyl-urea; and
- (c') N-(3-chloro-4-trifluoromethyl-phenyl)-N'-methyl-N'-n-butyl-urea.

Advantageously, in accordance with the present invention, in the foregoing formulae:

R₁ represents hydrogen; or alkyl having 1–4 carbon atoms, such as methyl, ethyl, n-propyl, isopropyl, n-butyl, isobutyl, tert.-butyl, and the like, particularly C_{1–2} alkyl; and

55 R₂ represents alkyl having 1–4 carbon atoms, as defined above, such as methyl to tert.-butyl inclusive, and the like, particularly C_{1–2} alkyl.

In accordance with a particular feature of the present invention, R₁ represents hydrogen or the same C_{1–4}, especially C_{1–2}, alkyl as R₂.

It will be realized by the artisan that all of the foregoing compounds contemplated by the present invention possess the desired selective or total herbicidal properties, and especially the capability of selectively destroying weeds, as well as a comparatively low toxicity toward warm-blooded creatures and a concomitantly low phytotoxicity with respect to higher plants, enabling such compounds to be used with correspondingly favorable compatibility with warm-blooded creatures and higher plants for more effective control and/or elimination of weeds by selective application of such compounds to such weeds and/or their habitat. Nevertheless, the instant compounds possess total herbicidal action when used in large quantities, although selective herbicidal action is obtained when

used in smaller quantities. As contemplated herein, the term "weeds" is meant to include not only weeds in the narrow sense, but also in the broad sense, whereby to cover all plants and vegetation considered undesirable for the particular purposes in question.

It will be appreciated that the instant specification and examples are set forth by way of illustration and not limitation, and that various modifications and changes may be made without departing from the spirit and scope of the present invention which is to be limited only by the scope of the appended claims.

What is claimed is:

1. N-(3-chloro-4 - trifluoromethyl - phenyl)-N',N'-dimethyl-urea.

2. N - (3-chloro - 4-trifluoromethyl-phenyl)-N',N'-diethyl urea.

3. N-(3-chloro-4 - trifluoromethyl - phenyl)-N'-methyl-N'-n-butyl-urea.
